UNITED STATES PATENT OFFICE.

WALTER P. SCHWEINFURTH, OF WESTFIELD, NEW JERSEY.

TAG OR LABEL.

1,371,266.

Specification of Letters Patent. Patented Mar. 15, 1921.

Application filed October 2, 1919. Serial No. 328,024.

To all whom it may concern:

Be it known that I, WALTER P. SCHWEINFURTH, a citizen of the United States, residing at Westfield, in the county of Union and 5 State of New Jersey, have invented certain new and useful Improvements in Tags or Labels, of which the following is a specification.

The present invention relates to tags or 10 labels of the more or less permanent type provided with a tablet such as a piece of slate, prepared card-board, or the like, upon which any desired marking or indication, generally of a temporary nature, may be 15 placed, and from which it may be readily erased or removed without injuring the tablet. The invention has for its object to provide an improved tag or label of this type of very simple construction, which is inexpensive to manufacture and which at the 20 same time is strong and durable.

To accomplish these objects I have provided a tag or label having a tablet disposed in a back or frame of sheet metal, from the 25 interior portion of which back the tongues are struck out in such manner that the periphery of the back is left intact so that it may be bent over forward to form a substantially complete peripheral rim or flange for 30 retaining the tablet in position. The tongues are employed as means for securing the tag itself. Other novel features of the invention will appear in the specification and be pointed out in the annexed claims.

35 I will now describe my invention with reference to the accompanying drawings in which:—

Figure 1 is a front view of a breeder's cage provided with a tag embodying my invention, to illustrate a practical use of the tag.

Fig. 2 is a front view of the finished tag.

Fig. 3 is a back view of the finished tag showing clearly the manner in which the 45 tongues are struck out from the back or frame and bent outward into position.

Fig. 4 is a back view of the tag showing the position of the tongues before they are bent outward into final position, and

50 Fig. 5 is a central sectional view along the lines 5—5 of Fig. 3.

Referring more specifically to the drawings, 10 indicates the frame or back of the tag or label, which back is preferably made from sheet metal. Before being formed as hereinafter described its contour or shape

is substantially the same as that of the tablet 11, which it embraces by having its periphery bent over forward (as shown in Figs. 2 and 5) to form a complete peripheral retaining rim or flange 12. Since this rim or flange extends completely around the periphery of tablet 11 the tablet is very effectively secured or retained by it, so that the finished article presents a neat and pleasing 65 appearance, and there is little likelihood of the tablet becoming loose or being accidentally displaced therefrom. The tablet is preferably made of slate or other material from which marks or indications may be 70 readily erased or removed, so that the tablet will not have to be removed when it is desired to place new markings upon it.

One or more tongues 13 of any desired shape are struck out from interior portions 75 of the back 10 and are bent outward substantially 180° on folding lines 14 located inside the periphery of the back. These tongues may be so cut as to leave the bridging portion 15, or the latter may be dispensed with if desired. The tongues are preferably soldered to the back 10 at the points 16 between the folding lines 14 and the periphery of the back. By locating the folding lines inside the periphery, as shown, 80 the latter is left intact so that the flange 12 is substantially continuous. This feature has the advantages that no projecting edges or corners are left exposed, and a very effective retaining flange for the tablet is thus provided. It will be noted also that by striking 85 out the tongues from the interior portion of the back instead of providing separate tongues, metal is utilized which ordinarily would not be required by the back to 90 perform its intended function, since the back is sufficiently strong after the tongues are cut therefrom. Furthermore, in order to manufacture the completed article only one 95 piece of metal is employed, which may be 100 of such shape, for instance square or rectangular, that in cutting out the blanks from a large sheet there is substantially no waste material. This is of considerable importance in that it makes the cutting operation 105 very simple and reduces the cost of production.

In Fig. 1, I have illustrated a tag embodying my invention, in a practical application of it to a breeding cage. In this 110 figure the numeral 17 designates the frame of the cage, having the hinged door 18, to

which is secured, by means of screws 19, the complete tag or label designated as 20. The tag in this case is used for the purpose of keeping thereon any desired records or information pertaining to the occupants of the cage, which records may be readily changed as desired.

I claim:—

1. A tag or label, comprising in combination a rigid tablet to receive an indication, a plane sheet metal back having a periphery of substantially the same contour as the periphery of said tablet and extending over and in contact with said tablet to unite the tablet with the back and tongues struck out from interior portions of said back, so as to leave the periphery intact, and projecting
- 10
- 15

beyond the edges of said back, to provide means for securing said tag or label in place.

20

2. A tag or label, comprising in combination, a rigid tablet to receive an indication, a plane sheet metal back having its edges extending forwardly and inwardly over the periphery of said tablet and in contact therewith to provide a substantially complete peripheral retaining flange for uniting the tablet and back, and tongues struck out from interior portions of said back and extending outwardly along the rear thereof to project beyond the edges of said back, and providing means for securing said tag or label in place.
